UNITED STATES PATENT OFFICE.

EDMUND SCHNABEL, OF NEW YORK, N. Y.

DESIGN FOR A PIANO-CASE.

SPECIFICATION forming part of Design No. 32,111, dated January 16, 1900.

Application filed November 4, 1899. Serial No. 735,832. Term of patent 7 years.

To all whom it may concern:

Be it known that I, EDMUND SCHNABEL, a citizen of the United States, residing in the borough of Bronx, in the city and State of New York, have invented and produced a new and original Design for Piano-Cases, of which the following is a specification, reference being had to the accompanying drawing, forming part hereof.

o Referring to the drawing, which is a perspective view of an upright-piano case embodying my design, the leading or material feature of the design is a central curved por-

tion of the piano-front with straight or plane portions on each side, the said central curved portion having a bowed-out or swell center with bays or concavities on each side thereof.

Having thus described my invention, what I claim, and desire to secure by Letters Patent, is—

The design for a piano-case as herein shown and described.

EDMUND SCHNABEL.
